Charles W. Warnick of Philadelphia Pa.
Letters Patent No. 312, Dated August 27, 1850.

The Schedule referred to in these Letters Patent and making part of the same.

To all whom it may concern:

Be it known that I, Charles W. Warnick of the County of Philadelphia, State of Pennsylvania have invented or produced a new Flat Top Cook Stove called the Flat Top Complete, and I do hereby declare that the following is a full and exact description of the same reference being had to the accompanying drawings of which Fig. 1 being a side elevation, Fig. 2 a front ditto, Fig. 3 a back ditto and Fig. 4 a view of one of the legs.

The general form is similar to that of other flat top cooking stoves having an oven and the usual conveniences for cooking in various ways.

My object in this design is to produce a compact stove, with a neat and ornamental exterior, with deep mouldings round the edges of the top, doors &c, and the panels being relieved by a neat scroll and floral pattern, varying in different parts but still in tasteful keeping with each other.

The words "Flat top complete" with "Patented" and the date are in raised letters over the doors in front and on the sides the words "Warnick Leibrandt & Co."

2

Des. 312

Around the edge of the hearth is a bead having the appearance of a twisted cord.

Your petitioner claims to be the original inventor or producer of the design and ornamental part of said Stove as above described and represented in the drawings.
